CLOTHES-WASHING MACHINE

Alwin Kost, Portland, Oreg.

Application February 12, 1947, Serial No. 728,061

5 Claims. (Cl. 68—172)

1

This invention relates to a clothes washing machine of a type in which a movable tub is subjected to a combined wabbling and oscillating movement to provide a highly efficient washing action.

My present invention is, in some respects, an improvement on devices disclosed in my prior patent No. 2,246,689, issued June 24, 1941, on a Mechanical Movement.

An object of this invention is to provide a clothes washing machine of simple construction that is highly efficient in operation and that is easy on the clothes that are being washed.

Another object is to provide a washing machine that is free from moving agitators and like parts that tend to injure and wear the clothes.

Another object is to provide a washing machine of movable tub type that is well balanced and substantially free from vibration when in operation.

Other objects of the invention will be apparent from the following description taken in connection with the accompanying drawings.

In the drawings:

Figure 1 is a view in vertical section, with parts in elevation, of a clothes-washing machine constructed in accordance with this invention.

Fig. 2 is a plan view of the same with parts in section taken substantially on broken line 2—2 of Fig. 1.

Fig. 3 is a detached sectional view taken substantially on broken line 3—3 of Fig. 2 and showing clutch shifting mechanism.

Fig. 4 is a wiring diagram showing electrical connections and control means for a motor and electromagnetic devices used in connection with this machine.

Fig. 5 is a fragmentary view showing alternative clutch control means that can be used in connection with this invention.

Fig. 6 is a fragmentary view of said alternative clutch control means looking in the direction of broken line 6—6 of Fig. 5.

Fig. 7 is a fragmentary sectional view showing alternative means for imparting oscillation to a post that supports a tub.

Fig. 8 is a fragmentary sectional view looking in the direction of line 8—8 of Fig. 7.

Like reference numerals designate like parts throughout the several views.

This washing machine comprises a tub 10 having spherical side walls 11, a bottom wall 12 and a removable cover 13. The top edge of the tub 10 is provided with a fixedly secured rubber seal ring 14 having an upwardly directed groove for

2

the reception of a down-turned edge portion 15 of the cover 13, whereby a leak tight connection is provided for the cover. Means such as a centrally positioned knob 16 is provided on the cover 13 to facilitate handling the same.

The bottom of the tub 10 is provided with an axially positioned inwardly projecting dome 17 that extends about half way from the bottom to the top of the tub. This dome 17 is shaped like a cone with a rounded or spherical top end. The dome 17 fits over and is secured to a dome shaped frame member 18 of strong and substantial construction that serves as a support for the tub. A flange ring 19 of angular cross sectional shape is permanently secured to the dome 17 of the tub 10 near the open bottom end of said dome 17. Screws 20 secure the flange 19 to the lower end portion of the dome shaped frame 18. Shim means 21 can be provided between the flange 19 and the bottom end of the frame 18, if needed, to insure a tight fit of the dome 17 over the dome shaped frame 18.

The interior of the tub 10 is provided with an annular baffle ring 22 of V-shaped cross section 23 located about mid way between the top and bottom of the tub. Also said tub 10 is provided at a plurality of spaced apart intervals with upright baffle members 22' of V-shaped cross section. The baffle members 22 and 22' augment the agitation and turbulence of the water in the tub and also serve as reinforcing members to greatly strengthen the walls 11 of the tub.

The tub 10 is mounted for oscillating and swash plate movement within a cylindrical housing 23 that is supported on legs 24. The spherical walls 11 of the tub are disposed in close proximity to, but not in contact with, a reinforcing ring 25 that is provided on the top edge portion of the cylindrical housing 23. The working clearance 26 between these two parts is close enough to preclude all possibility of persons getting fingers or other parts of the body caught between said two parts when the machine is in operation.

Arcuate frame members 26 are provided between the legs 24. Transverse frame members 27 are connected with the arcuate frame members 26 to form supporting means for the devices on which the tub is movably mounted.

The tub supporting and mounting means comprises a dish shaped housing 28 carried by the transverse frame 27 and having a cover member 29 secured thereto, as by flange and bolt means 30. The cover member 29 has a medially disposed upwardly projecting tubular portion 31 of

frustro-conical shape extending upwardly into the frame member 18 and dome 17. An inclined post or shaft 32 extends upwardly through the tubular member 31 and has its upper end portion secured to the dome shaped frame 18, preferably by threading the upper end portion of the post 32 into a hub 33 of the frame 18 and providing a key 34 to prevent relative rotary movement of these two parts.

The inclined post 32 has a ball 35 rigidly connected therewith near its upper end. The ball 35 is mounted for universal movement in self-lubricating bearing means 36 that is carried by the upper end portion of the housing member 31. A cap 37 holds the bearing means 36 in place. The ball 35 can be integral with the inclined shaft 32 and the weight of the tub is carried by this ball 35.

The lower end portion of the inclined post 32 is disposed within an off center inclined bearing socket 38 in a worm wheel 39. The worm wheel 39 is rotatively mounted on an upright bearing pin 40. The pin 40 is supported in a hub 41 that extends downwardly from the housing member 28. Preferably inclined brace or truss members 42 extend between the hub 41 and some of the legs 24 to reinforce and strengthen the frame structure.

Obviously rotation of the worm wheel 39 will move the inclined post in a double conical path with the center of movement of said post coinciding with the center of the ball 35. This will impart a wabbling or swash plate movement to the tub 10.

The inclined post 32 is also connected with means for imparting to said post an oscillatory movement simultaneously with the movement of said post in a conical path.

This post oscillating means comprises a forked bracket member 43 that fits over the shaft 32 and is connected therewith by a cross pin 44. The forked member 43 is rigidly secured to a bracket arm 45. The arm 45 is disposed substantially at right angles to the axis about which the inclined post 32 moves. Said arm 45 is supported in bearing members 46 in a tube 47. The tube 47 has two oppositely projecting bearing members 48 and 49 that are positioned vertically and at right angles to the arm 45 and are mounted for oscillation in bushings 50. One of the bushings 50 is supported by the lower housing member 28 and the other bushing 50 is supported by a cap 51 that is threaded into the housing cover 29. The cap 51 is locked to the cover 29 by a set screw 52. The cap 51 is used for the purpose of facilitating application and removal of the housing cover 29 and allows the cover 29 to be positioned at right angles to the shaft 32 for purpose of assembly and disassembly.

The worm wheel 39 is driven by a worm 53 that meshes therewith. The worm 53 is carried on a shaft 54 which is journaled in bearings 55 in the housing 28. A packing 56 is provided in one of the bearings 55 to prevent leakage of oil. The shaft 54 extends outwardly through the bearing 55 that carries the packing 56 to the exterior of the housing and has two relatively telescopic clutch members 57 and 58 mounted thereon. The clutch member 57 is of the cone-friction type and is splined on the shaft 54 by key members 59. The other clutch member 58 receives the cone member 57 and is rotatively mounted on the shaft 54. The cone member 57 preferably has lining material 60 secured thereto. A bushing 61 is preferably provided between the clutch

member 58 and the shaft 54. A spring 62 which thrusts against a collar 63 yieldingly urges the cone member 57 toward the other clutch member 58.

5 The clutch member 58 has a driving connection by means of a belt 64 with a pulley 65 on the shaft 66 of a motor 67. The motor 67 is preferably suspended from the horizontal frame members 26 and 27.

10 The clutch member 57 has a shoulder 68 that is engaged by a forked shifter bracket 69, by which said clutch member is moved against the pressure of the spring 62 into a disengaged position. The shifter bracket 69 is rigid with a 15 sleeve 70 that is secured to a rod 71. The rod 71 is guided for longitudinal movement in brackets 72 and 73 that are rigid with the frame 27. A spring 74 provided between the bracket 72 and sleeve 70 urges the shifter bracket 69 into disengaged position relative to the shoulder 68. A 20 solenoid 75 having a movable plunger 76 is positioned adjacent to and in alignment with the rod 71 and is adapted to move the shifter bracket 69 against the pressure of the two springs 62 and 25 74 into a disengaged position. When the solenoid 75 is energized the plunger 76 will press against and move the rod 71.

30 Preferably the motor 67 and solenoid 75 are wired as diagrammatically shown in Fig. 4 so that the circuit to the solenoid 75 can be opened and closed whenever the motor 67 is operating but so that the circuit to the solenoid can not be closed when the motor circuit is open. This can be done as follows: by using a common connector 77 to connect one terminal of an electric plug 78 with one terminal of the solenoid 75 and one terminal of the motor 67; by using conductors 79 and 80 and switch 81 to connect the other terminal of the motor with the other terminal of the plug 78; and by connecting the other terminal of the solenoid 75 by a conductor 82 and switch 83 with the motor circuit conductor 79 between the motor 67 and the switch 81. From the foregoing description it will be seen that the motor 67 can be started or stopped at will by closing or opening the switch 81 and that the solenoid can be energized or de-energized at will by closing or opening the switch 83 when the switch 81 is closed but will always be de-energized when the motor control switch 81 is open.

35 If desired the solenoid 75 can be dispensed with and manually operated means, as shown in Figs. 5 and 6, can be used for moving the rod 71 to disengage the clutch. This manually operated means comprises a cam member 84 positioned adjacent the end of the rod 71 and secured to a shaft 85 that is mounted in bearing means 86. A lever 87 is connected with the shaft 85 as a means for oscillating the shaft. A spring 88 40 normally holds the cam 84 in the inoperative position shown in Fig. 6. Preferably a recess 89 is provided in the highest point of the cam 84 to receive the rounded end of the rod 71 when this part of the cam is in engagement with the 45 rod. When the end of the rod 71 is seated in the recess 89 the clutch will be held in a disengaged position irrespective of the pull of the spring 88 until the lever 87 is manually operated to move the cam 84 into a released position relative to the rod 71 whereupon the spring 62 will move the clutch cone 57 into engagement with the clutch member 58.

50 The tub 10 has a water outlet 90 covered by a screen 91 and connected by a flexible conduit 78 92 with an outlet control valve 93 by which the

draining of water from the tub can be controlled.

Wringing means of conventional form can be provided and driven from a vertical shaft 94 that is connected by worm drive means 95, stub shaft 96 and flexible coupling 97 with the motor shaft 66.

Figs. 7 and 8 show modified and simplified means for imparting oscillation to a tub supporting post 100 that corresponds to the post 32 of Fig. 1. In this construction of Figs. 7 and 8 the gear housing comprises parts 101 and 102 of simplified construction. The post 100 has an enlarged portion 103 provided with an elongated opening 104 and a bracket member 105 which corresponds to the member 43, 45 of Fig. 1 is mounted for swinging movement on a vertical pivot 106 and extends through the opening 104 in the post 100. Preferably a sleeve 107 that is externally square in cross section is provided on the bracket 105. The bracket 105 will oscillate the post 100 on its own axis as said post is moved in conical paths by the rotation of the gearwheel 39.

In the operation of this clothes washing machine water is placed in the tub to about the level of the baffle member 22, the clothes to be washed are placed in the tub, the motor 67 is started and the clutch 57, 58 engaged. This will drive the gearwheel 39 and move the tub supporting post 32 in a double conical path so as to impart a wabbling or swash plate movement to the tub. At the same time the bracket member 45, 43 will act as a lever arm to oscillate the post 32 on its own axis and this oscillation will be imparted to the tub 18. This combination of movements of the tub imparts to the water and clothes a complex movement that is highly efficient and fast in washing and cleaning said clothes. At the same time this movement of the tub and the water and clothes therein is fairly well balanced and is not productive of objectionable vibration.

The vanes 22 and 22' are beneficial in helping to impart movement to the water and the clothes. The spherical shape of the tub helps to prevent water from splashing up against the cover of the machine. The sealing of the cover by the ring 14 prevents leakage of water. The vanes 22 and 22' also greatly reinforce and strengthen the walls 11 of the tub. All bearings and bushings in the machine are of self lubricating type so that the machine will not require other lubrication. The tub 18 does not have any agitator or moving part and consequently no oscillating or rotating shaft extends into the tub.

Obviously changes in this invention can be made within the scope of the following claims.

I claim:

1. A washing machine comprising an upright post supported for tilting and rotative movement about a center intermediate its length; a tub carried by the upper end portion of said post; and means for simultaneously oscillating said post on its axis and moving said post in conical paths about its center of movement.

2. A washing machine comprising an upright post supported for tilting and rotative movement about a center intermediate its length; a tub carried by the upper end portion of said post; means for moving said post in a double conical path about the center on which it is mounted and means for simultaneously oscillating said post on its own axis.

3. A washing machine comprising a tub; an in-

dented portion in the bottom of said tub extending for a substantial distance into said tub; an upright post extending into said indented portion and having its upper end portion rigidly connected with said tub for supporting said tub on said post; a universal bearing for said post positioned within said indented portion and near the upper end portion of said post; means for moving said post in conical paths with said bearing as a center to thereby impart a swash plate movement to said tub and means for simultaneously oscillating said post on its own axis.

4. A washing machine comprising a tub; a relatively large dome shaped indented portion in the bottom of said tub extending substantially to the center of said tub; an upright post extending into said indented portion and having its upper end portion rigidly connected with said tub for supporting the same; a bearing support extending upwardly into said indented portion; a universal bearing for said post carried by said bearing support and positioned near the upper end portion of said post; means for moving said post in conical paths with said bearing as a center to thereby impart a swash plate movement to said tub and means for simultaneously oscillating said post on its own axis.

5. A washing machine comprising a frame; a gear housing supported by said frame; a bearing support extending upwardly from said gear housing; a spherical bearing carried by the upper end portion of said support; a gearwheel in said housing; an eccentric socket in said gearwheel; a post mounted in said eccentric socket and extending upwardly through said bearing support; a spherical member rigid with said post journaled in said spherical bearing; a dome shaped frame member fixedly secured to the upper end portion of said post and extending downwardly over said bearing support; a tub having in its bottom an axially disposed upwardly indented dome shaped portion that is fitted over and secured to said dome shaped frame member; means for rotating said gearwheel to move said post in conical paths;

45 an elongated bracket arm having on one end a forked member connected with said post by pivot means transverse to said post, said elongated bracket arm being positioned substantially at right angles to said post; guide means supporting said elongated bracket arms for longitudinal movement; and pivot means for said guide means positioned transverse to said elongated bracket arm and parallel to the axis about which said post is moved whereby said bracket arm will oscillate said post as said post is moved in a conical path.
